LAPPING OR ABRADING TOOL

William E. Hoke, Baltimore, Md.

Application July 27, 1937, Serial No. 155,845

4 Claims. (Cl. 51—206)

Fuel pumps and injection nozzles of small size high speed Diesel engines must function with a high degree of accuracy, in view of the very small quantities of fuel injected for each working stroke of the engine. In the case of an engine running at 2000 R. P. M. injection may have to be completed in about .002 of a second and if the engine is of a four cycle type, each fuel pump and injection nozzle must go through the injection process 1000 times per minute. If the engine is of the two cycle type, at 2000 R. P. M., injection must occur 2000 times per minute for each cylinder. The sizes of the fuel pump and injection nozzle of such an engine are so small that it is not practical to use piston rings or other means to insure accurate fitting. The plungers and cylinders must be lapped with a clearance not to exceed .0001 of an inch and to obtain such accuracy has been a very difficult problem in this art heretofore. The outer cylindrical member of the injection nozzle and fuel pump are not only hardened but nitrided before being lapped for final use. The hardening process, if done after the lapping, would so warp the surfaces that they 25 would lose their accuracy of fit, and cause leakage.

By my two patents both dated March 11, 1924, and numbered 1,486,338 and 1,486,344 processes and mechanism for lapping a number of articles 30 and finishing them so that they are identical has been set forth. These processes and the mechanism may be used to make the pistons of the fuel pump and of the injection nozzle but up to the present time no method has been known for 35 making the inner cylindrical surfaces of the fuel pump and of the injection nozzle accurate in their fit with the pistons. Previous practice has been to make a plurality of pistons and then finish each cylindrical part to fit that particular piston 40 and this process is not only very tedious but also very expensive.

By the processes of this invention inner cylindrical surfaces of an accuracy of 1,000,000th. of an inch can be obtained and numbers of such 45 cylinders may be made at one time, which are all identical, to thereby avoid the necessity of fitting each cylinder or bore to a respective piston. Accurate fitting of cylinders and pistons will prevent leakage even at the high pressure of 800 50 pounds per square inch to which the pumps and nozzles are subjected.

The invention utilizes the symmetrical distribution of errors to correct the errors occurring in a plurality of such bores. If a plurality of such 55 bores are arranged in order it will be found that

some are too small, perhaps each of varying degree and perhaps some are the correct size. These may all be brought to a proper and identical size by lapping. If each bore is lapped a small quantity in a regular sequence or order with the same lap a small amount of metal is taken from each bore that is too small and the bores already at size are not affected by the passage of the lap. The amount of lapping given to each cylindrical surface is so small as scarcely to make any wear 10 on the lap itself. The sequence of the lapping of the group of bores may be varied in any predetermined manner so that all of the errors occurring in the sizes of the bores may be finally eliminated, 15 by successively lapping and varying the sequence.

The lap usually consists of a cylindrical member substantially the size of the cylindrical surfaces to be lapped, made of wax, wood, lead, aluminum or copper or some such material having charged into its surface a suitable abradant 20 such as emery, "alundum," "corborundum" or diamond dust.

It is one of the objects of this invention to make this lap of a material having a differential thermal expansion from the metal of the bores so that 25 in the warming of the lap and the bores the lap will expand more rapidly than the bores and thereby cause the lap to continue its abrading action on the bore. When it is desired to lessen the abrading action of the lap on the bore the 30 bore and lap will be cooled, and the metal of the bore contracting more rapidly due to the cooling will thereby lessen the abrading action of the lap on the bore.

In the use of the usual cylindrical lap there is 35 a tendency for the lap to wear unequally and thereby to bell-mouth the cylindrical surface being lapped. In lapping the part of the cylindrical surface furthest removed from the lap entry and exit end, the complete length of the lap passes 40 the entry and exit end more often and consequently gives it more lapping than the far end. This wearing effect on the lap and the unequal lapping of the lap entry and exit end may be partially overcome by making the laps slightly 45 shorter, when working in a blind bore, than the cylindrical surfaces so that the closed end of the bore may be abraded slightly more than the open end by abrading with the complete lap within the cylindrical surface. When the bore being 50 abraded is open at both ends a lap only slightly longer than the cylindrical opening may be used and the abrading action made greater at the end of the bore away from the lap support than at the entry and exit end, that toward the lap support, 55

so as to equalize the abrading at the far end of the cylindrical surface with the excess lapping obtained on the entry and exit end of that surface due to the passage of the complete lap along that end, or the bore may be reversed end for end.

The lap may also be made in two parts, transversely, and attached together at their ends and also to the support. By varying the relative positions of the two sections of the lap or by reversing the full lap on its support a more equal wear on the total lap is obtained and this equal wear on the total lap likewise produces a more equal abrading of the complete cylindrical surface of the bore being lapped. By this construction the errors occurring in the lap are symmetrically distributed.

The support of the lap on its arbor should also be resilient to allow for a lateral flexing of the lap in its rotation, preferably this should be a bodily flexibility of the lap on its arbor so as to avoid any rigid movement of the lap in the bore caused by its support and rotation from its arbor.

With these and other objects and advantages in view, the invention consists of the features of construction and operation and the methods described in the following specification and illustrated in the accompanying drawings in which a diagrammatic form of an apparatus embodying the essentials of the mechanical features of the invention are shown. Also there are shown illustrative arrangements of the lap to obtain the purposes of the invention.

Referring to the drawings:

Figure 1 is a plan view of an apparatus for holding a plurality of articles to be lapped.

Figure 2 is a side view of the same with the container wall shown in section.

Figure 3 is a detailed view of a catch to hold the article clamping means in place.

Figure 4 is a view of a lap showing a flexible connection with its arbor.

Figure 5 is a similar view showing a modified form of connection.

Figure 6 is a further modified form of lap shown lapping an open-ended article.

Figure 7 is a sectioned lap operating on a similar article.

Figure 8 is a view of the top of the lap shown in Fig. 7 with the arbor removed.

Figure 9 is a view of the sectioned lap operating on a blind-ended article.

Figure 10 is an enlarged view of an alternate form of connection of a lap with its arbor.

Figure 11 is a plan view of the lap shown in Fig. 10 with its arbor removed.

In Figs. 1 and 2, the container 1 having therein a liquid or other heat transfer fluid, has a standard 2 at its center supporting a plate 3 freely rotating on ball bearings 4. This plate 3 has a plurality of openings 5 arranged symmetrically therein and each opening 5 has an index number 6. In each opening 5, and there are shown 36 of such openings, there is placed the article 7 to be lapped. In these views such articles are shown to be injection nozzles for Diesel engines. As shown these nozzles have a closed or blind lower end and an open entry and exit end with a shoulder 8 which rests upon the plate 3. The plate 3 is cut away as shown at 9 to facilitate uniformity of heat transfer.

The standard 2 has projecting from its center, standard 10 on which is pivoted lever 11. The container 1 has preferably equally distributed around its diameter three supports 12 which serve to maintain the plate 3 in a horizontal po-

sition. Over one of these supports 12 and hinged to the side of the container 1 is a clamp 13 which has in its center, when horizontal, a vertical opening 14 substantially the size of the bore of the article to be lapped. This opening is slightly flared at its top 15 to form a lead for the lap.

The lower portion of the clamp 13, concentric with the opening 14, has a gripping opening 16 to firmly clamp the article to be lapped against the plate 3. The clamp 13 at its sides is cut out as shown at 17 to avoid striking adjacent articles. The clamp 13 has at its free end a link 18 pivoted for free vertical angular movement therein, and at the top this link has an elongated slot 19 therein to allow free vertical movement of a pivot 20 in the lower end of the lever 11.

This link 18 has surrounding it a spring which bears against clamp 13 and the free play allowed by the slot 19 allows the lower end of the lever 11 to resiliently press the clamp 13 upon the top of one article 7. The other end of this lever 11 is held in this resilient holding position by a catch 21 pivoted to a standard 22 on the container wall 1, as shown in Fig. 3. The liquid level in the container is preferably above the top of the articles 7 and paddles 22a may be placed on the bottom of plate 3 to slightly agitate the liquid to make more uniform the transfer of heat therethrough.

An electric coil 23 is placed in the bottom of the container in order to heat the liquid to a given amount and to maintain the temperature that is desired. This electric coil 23 may be energized through a thermostatically-operated switch 24 which is operated by the thermostat bulb 25 placed in the bottom of the container and preferably in the neighborhood of the article being lapped. As a guide to the operator a thermometer 26 may also be in the liquid.

When it is desired to lower the temperature of the fluid this could be done by any mechanical means or the fluid therein, which is preferably some neutral oil, could be withdrawn through a valve or outlet 27 and colder fluid placed in the container.

Practically any form of drill press may be used having a chuck to hold the lap and to rotate it and to allow it to be raised and lowered at the will of the operator. In Fig. 2 a chuck 28 is shown containing a lap 29 held by its arbor 30 in the chuck.

In Fig. 4 an arbor 30 is shown having a key 31 which may be driven tightly therein and removed at will. The lap 29 shown in this view has a slightly enlarged central bore 32 to allow free play of the lap on the arbor. The opening 33 transversely of the lap is larger than the ends of the key 31 to allow comparatively free play of the lap on the key, although rotary motion is of course transferred to the lap by means of the key.

By means of this structure the lap may be changed end for end at will upon removal and reinsertion of the key, and the lap is allowed to wobble and not maintain any fixed path of revolution due to the fixation of the path of revolution of the arbor. In this way the lap adjusts itself to the bore in the article being lapped.

In Fig. 5 an alternative structure for accomplishing this same purpose is shown and in this view an arbor 34 has thereon screw threads 35 which fit loosely in screw threads 36 on the lap. Due to the intermittent and irregular movement of the arbor the loose screw threads allow the lap to have a floating movement on the arbor and thus accomplish substantially the same result as the construction shown in Fig. 4.

A further means of accomplishing substantially the same result for a lap intended to operate on an open-ended article is shown in Fig. 6. In this view not only do the screw threads 37 fit loosely in the lap 38 but the arbor 39 is pressed in on both sides in two places at right angles to each other as shown as 40, which allows resiliency of the arbor universally.

In Fig. 7 a sectioned lap is shown for operating 10 on an open-ended article. In this connection the lap is made in two identical transverse sections 41, each section being a small cylinder and each section having three clutch faces 42 projecting from each end. These clutch faces and the 15 spaces allowed therebetween allow a loose connection while imparting rotary movement between the sections of the lap. The arbor 43 has similar clutch faces at its lower end and a rod 44 is threaded into the arbor 43 and has at its 20 lower end a nut 45 to hold the sectioned lap resiliently on the arbor while maintaining its rotation with the arbor.

Instead of using these clutch faces, loose screw threads 46 in the sections 41 of the lap, as shown 25 in Fig. 9, may be used and these sections may be fastened together by a bolt 48 loosely attaching them and they may be attached to the arbor 49 by means of the threaded member 50 having thereon a clutch face similar to that shown in 30 Fig. 8 and the circumference of which has a groove 51 therein, around which is a spring wire ring 52. This clutch member also fits loosely to allow for play laterally between the lap and the arbor.

35 In Fig. 10 a clutch form of connection between arbor and lap is shown which might be used instead of the connection shown in Fig. 6. In this view the clutch portions 54 on the arbor 53 and 55, on the lap 56 are circumferentially grooved at 57 and in this groove is placed the spring ring 58.

Because of the reversible feature of the lap, uniformity of wear on the lap is produced and that uniformity promotes uniformity of lapping 15 in the article. By making the lap in two sections, eight variations of arrangement of the lap on its arbor are available. If the lap shown in Fig. 9 be considered and the respective ends of the sections be lettered as shown the following arrangements are possible:

50 A B A B C C D D
B A B A D D C C
C C D D B A A B
55 D D C C A B B A

By this means both barrelling and spooling of both lap and bore are avoided and the errors which creep in due to wear on the lap are symmetrically distributed.

60 This result is also furthered by the use of a lap slightly shorter than a blind bore, in which, after the lap is completely inserted in the bore, it is reciprocated a few times near the blind end of the bore and without abrading the entrance and exit portion at the same time. Or, in the same manner, with an open-ended bore, a lap longer than the bore may be inserted beyond the entrance and exit end, and the further end 65 of the bore abraded without abrading that entrance and exit end, or the bore may be reversed end for end.

It will of course be understood that in the use 70 of the invention, with each vertical movement 75 of the lap into the bore and the withdrawal there-

from, only a very small amount of metal is removed and the invention contemplates lapping each of the articles a number of times in any predetermined sequence this small amount. If the sequence were always the same, due to the infinitesimal wear on the lap the articles finally lapped would be lapped less than those initially lapped, and therefore this sequence must be varied and perhaps every other article lapped in one course; and then the articles skipped 10 lapped the next time around or perhaps every third article may be lapped in one circumferential trip around; and then another third picked up on the next trip and the final third on the succeeding trip; or one group of nine might be 15 chosen and another group symmetrically around the circumference of a plate might be lapped, and then the omitted articles would be next lapped. By this process of lapping in a varied sequence the errors which would creep in due to 20 the wear on the lap may be made infinitesimally small and by varying the temperature between any sequence a larger or less amount of abrading may be accomplished by the corresponding movements of the lap. Likewise, by varying the 25 positions of the lap on its arbor further errors that creep in due to lap wear are eliminated and thus a multiplicity of uniform bores are produced which have the precise size originally desired.

It will of course be understood that certain of 30 the processes of this invention may utilize the special lapping rod shown in Fig. 10 of my Patent 1,486,338, above referred to, or other similar mechanically expanded laps.

Furthermore, it is to be understood that the 35 particular forms of apparatus shown and described and the particular procedures set forth, are presented for purposes of explanation and illustration and that various modifications of said apparatus and procedures can be made without departing from the invention as defined in the appended claims.

The claims herein relate to lapping or abrading tools. In two other applications, divisions in part of this one, I claim the apparatus herein disclosed 45 and the method of lapping or grinding herein disclosed, respectively.

What is claimed is:

1. A lapping tool comprising, in combination, a 50 supporting member adapted to be rotated and reciprocated during a finishing operation, a longitudinally and circumferentially homogeneous lap having a continuous cylindrical surface, whereby said lap varies uniformly in circumference with variations of temperature, and means in said lap 55 and on said supporting member to attach the same together to allow either end of said lap to be made the leading end including interlocking means to prevent relative rotation between said lap and member.

2. A lapping tool comprising, in combination, a supporting member adapted to be rotated and reciprocated during a finishing operation, a longitudinally and circumferentially homogeneous lap having a continuous cylindrical surface, whereby 65 said lap varies uniformly in circumference with variations of temperature, and means in said lap and on said supporting member to attach the same together to allow either end of said lap to be made the leading end, and to allow a measure of lateral movement of said lap with respect to said support including interlocking means to prevent relative rotation between said lap and member.

3. A lapping tool comprising, in combination, a 70

supporting member adapted to be rotated, and reciprocated during a finishing operation, a longitudinally and circumferentially homogeneous lap having a continuous cylindrical surface, whereby said lap varies uniformly in circumference with variations of temperature, and composed of transverse sections, and means to attach said sections and supporting member together, to allow either end of said lap and of said sections to be made the leading end including interlocking means to prevent relative rotation between said member, lap and sections.

4. A lapping tool comprising, in combination, a supporting member adapted to be rotated, and

reciprocated during a finishing operation, a longitudinally and circumferentially homogeneous lap having a continuous cylindrical surface, whereby said lap varies uniformly in circumference with variations of temperature, and composed of transverse sections, and means to attach said sections and supporting member together, to allow either end of said lap and of said sections to be made the leading end, and to allow a measure of lateral movement of said lap with respect to said support including interlocking means to prevent relative rotation between said member, lap and sections. 5 10

WILLIAM E. HOKE.
